COMBINED SPOT LIGHT AND PLUG THEREFOR

Arthur Schifrin, 1144 Bay Blvd.,
Atlantic Beach, N.Y. 11509

Filed Nov. 9, 1970, Ser. No. 25,871

Term of patent 14 years

Int. Cl. D26—02

U.S. Cl. D48—20

FIG. 1

FIG. 2

FIG. 4

FIG. 5

FIG. 3

FIG. 1 is a front elevational view of a combined spot light and plug therefor, showing my new design;

FIG. 2 is a side elevational view, the opposite side being a mirror image thereof;

FIG. 3 is a rear elevational view thereof;

FIG. 4 is a top plan view thereof; and

FIG. 5 is a bottom plan view thereof.

The cord is broken away in FIGS. 1 through 5 to indicate indeterminate length.

I claim:

The ornamental design for a combined spot light and plug therefor, substantially as shown and described.
